S. S. MARLEY

BREAD TOASTER

Filed Dec. 3, 1920

FIG. 1.

FIG. 2.

S. S. MARLEY, Inventor

Chas. E. G. Marley
Assignor

UNITED STATES PATENT OFFICE.

SAMUEL S. MARLEY, OF WILMINGTON, DELAWARE.

BREAD TOASTER.

Application filed December 3, 1920. Serial No. 428,069.

To all whom it may concern:

Be it known that I, SAMUEL S. MARLEY, a citizen of the United States, residing at Wilmington, in the county of New Castle 5 and State of Delaware, have invented a new and useful Bread Toaster, of which the following is a specification.

It is the object of this invention to provide a toaster, the jaws of which may be 10 fashioned cheaply out of wire or like material.

Another object of the invention is to provide novel means for assembling a handle with the jaws.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, within 25 in the scope of what is claimed, changes in the precise embodiment of the invention shown can be made without departing from the spirit of the invention.

In the accompanying drawings:—

30 Figure 1 shows in plan, a toaster constructed in accordance with the invention, the handle being in section; Figure 2 is an elevation of the toaster, the handle being in section.

35 The toaster is fashioned from a single strip of material, preferably wire, one end 1 of the strip being prolonged to form a loop-shaped jaw 2, one side 3 of the jaw being extended to fashion a loop-shaped arm 4 disposed longitudinally of the end 1. One side 5 of the arm 4 merges into a second loop-

shaped jaw 6 cooperating with the first specified jaw 2, one side 7 of the second jaw 6 being formed into a binder 8 embracing the end 1 and the arm 4. The binder 8 is prolonged to create a helical handle 9 surrounding the end 1 and the arm 4, the arm and said end constituting a stiffener, resisting the lateral bending of the handle 9.

The bread or other material which is to 50 be toasted is held between the jaws 6 and 2, at the outer ends thereof, owing to the resiliency of the jaws.

The toaster comprises a pair of cooperating resilient loop-shaped jaws, each including a bend and side arms converging to a point of meeting and a handle connected to the arms of both jaws at the point of meeting.

Having thus described the invention, what is claimed is:

60 A toaster composed of a single piece of wire bent to form a loop-shaped jaw with one side thereof extending longitudinally and its inner end bent to form a longitudinally extending loop-shaped arm, one side 65 of said arm merging into another loop-shaped jaw superposed on and cooperating with the first mentioned jaw, one side of the second jaw being wound around said arm and end at their junction with said 70 jaws to form a binder, said binder being prolonged and formed into a helical handle encompassing said end and arm which constitute a stiffener for the handle.

In testimony that I claim the foregoing as 75 my own, I have hereto affixed my signature in the presence of two witnesses.

SAMUEL S. MARLEY.

Witnesses:

HARRY I. GILLIS,
ELIZABETH S. MARLEY.
